UNITED STATES PATENT OFFICE

2.161.212

SUBSTITUTED BARBITURIC ACIDS CONTAINING QUATERNARY CARBON ATOMS

Frank C. Whitmore, State College, Pa., and Melvin A. Thorpe, St. Louis, Mo., assignors to Malineckrodt Chemical Works, St. Louis, Mo.

**No Drawing. Application November 3, 1934,
Serial No. 751,416**

5 Claims. (Cl. 260—257)

This invention relates to substituted barbituric acids, and with regard to certain more specific features, to 5-substituted barbituric acids including at least one substituent alkyl group embodying a quaternary carbon atom.

This application is in part a continuation of our copending application, Serial No. 666,508, filed April 17, 1933, and entitled "Barbituric acid derivatives."

10 Among the several objects of the invention may be noted the provision of 5-substituted barbituric acids corresponding to the type formula:

wherein Y indicates hydrogen or alkali metal; and the R's indicate alkyl or other substituent groups (as pointed out more fully hereinafter), but at least one of the R's indicates an alkyl substituent containing a quaternary carbon atom, that is, a carbon atom to which are linked four other carbon atoms; or the ordinary substitution products thereof. Other objects will be in part obvious and in part pointed out hereinafter.

The invention accordingly comprises the elements and combinations of elements, and features of composition, which will be exemplified in the substances hereinafter described, and the scope of the application of which will be indicated in the following claims.

35 cated in the following claims.

It has heretofore been determined that the effectiveness of substituted barbituric acid derivatives as hypnotics, sedatives, or soporifics, depends in part upon the composition of the substituent groups, and it has also been noted that the more branched the substituent groups are, the more effective is the hypnotic or sedative or soporific action, without corresponding increase 40 in undesirable qualities. It is the purpose of the present invention to provide for substituted barbituric acids having substituents including a considerable number of branches through the use of substituents containing a quaternary carbon atom, which substituents are all broadly new. Such derivatives have not heretofore been prepared because no satisfactory method has been known for obtaining the quaternary carbon-containing substituent in such form as to 45 permit of its joining to the barbituric acid nucleus. However, such a method has now been provided, and, as set forth in the copending application of the present applicant Whitmore, and Walter E. Trent, Serial No. 666,510, filed April 50 17, 1933, now Patent No. 2,022,485, dated November 26, 1935, halides including a quaternary carbon atom, such as 3,3-dimethyl-1-bromobutane, may readily be prepared. In the copending application of the present applicant Whitmore and 55 August H. Hornecker, Serial No. 36,132, filed Au- 60

gust 14, 1935, the preparation of higher homologous halides, such as 4,4-dimethyl-1-bromo-pentane, is disclosed.

Numerous examples of substances within the scope of the invention are set forth hereinafter, and for an exemplary number of these examples, details of procedure for the preparation thereof are set forth. It is to be understood, however, that the invention is by no means limited to the specific examples set forth. 5 10

The first group of examples, numbered 1 through 5, show variations in the structure of the substituent R (in the above type formula) containing the quaternary carbon atom, while the other R is uniformly the substituent ethyl. 15

EXAMPLE 1

5-ethyl, 5-(3',3'-dimethylbutyl) barbituric acid

The structural formula of this substance is as follows:

The above substance is prepared in the following manner:

Ethyl ethylmalonate, commercially obtainable, is used as a starting material. This substance is condensed, in absolute ethyl alcohol in the presence of an alkali alcoholate, with 3,3-dimethyl-1-bromobutane, according to the following reaction:

The product of this reaction, the formula for which is given above, is then condensed with urea, the reaction proceeding in the following manner:

60 August H. Homeyer, Serial No. 36,132, filed Au-

the product being the desired substituted barbituric acid.

Procedure

5 150 cc. of ethyl alcohol were distilled from a solution of absolute ethyl alcohol plus one-twentieth of its weight of metallic sodium into a three-neck flask. The flask was placed in an oil bath and a condenser holding a drying tube 10 at the upper end, and a stirrer with a mercury seal, and a dropping funnel were placed in the three necks. 6.9 grams of metallic sodium weighed in toluene were added in small pieces 15 through the condenser over a period of about 7 minutes. Then, with the oil bath at a temperature of about 80° C., 56.4 grams of ethyl ethyl-malonate (boiling point, 112 to 115° at 30 to 32 mm. pressure) were added and the mixture was 20 stirred for about one-half hour. Then, during the next two hours, 49.5 grams of 3,3-dimethyl-1-bromobutane (boiling point, 137 to 138° C. at 25 740 mm. pressure), were added to the mixture. After about one-half hour, sodium bromide began to settle out. The mixture was then stirred and refluxed for 56 hours, at the end of which time the mixture was just faintly alkaline to litmus paper. The flask was then attached to a fractionating column and the excess alcohol distilled off. The residual mixture was washed with 30 120 cc. of water and the oily layer allowed to separate. The water layer was extracted once with ether, and the ether was then added to the oily fraction, which was then dried with sodium carbonate. The dried oily fraction was then 35 fractionated, and the product ester (see structural formula above), was obtained to the extent of 36.1 grams, boiling at from 148 to 151° C. The yield was 44% of theoretical. The index of refraction of the product ester was about 40 1.4320 at 20° C., with respect to the sodium-D line.

The same flask arrangement was used for the second step. 65.97 grams of absolute ethyl alcohol were placed in the flask, and 3.84 grams of 45 clean metallic sodium were added to form sodium ethylate. The resulting ethylate was cooled to 20° C., and 15.15 grams of the ester prepared as above were added, followed by 4.81 grams of pure, crystalline urea. The reaction mixture was 50 heated to refluxing temperature by means of a water bath, and the refluxing was continued for four hours. A straight condenser was then attached to the flask, and the excess alcohol was removed by distillation. This required two hours. 55 The residue in the flask was then cooled to 25° C., and then dissolved by adding 50 cc. of distilled water. The resulting solution was then extracted with two portions of ether, 50 cc. and 25 cc. respectively. The extracted solution was 60 then diluted with an additional 50 cc. portion of water and the barbituric acid derivative precipitated out by adding dilute hydrochloric acid until the solution was acid to blue litmus paper. 65 The almost white crystalline precipitate was washed with water, sucked free of excess water, and then dried in an electric drying oven over night at 105° C. The product weighed 9.35 grams, which was 70% of the theoretical yield. This 70 product was then dissolved in 107 cc. of boiling 50% ethyl alcohol. On cooling, 8.5 grams of pure white crystals were obtained. These crystals had a melting point of about 192° C., and constituted the desired product, 5-ethyl, 5-(3',3'-dimethylbutyl) barbituric acid.

EXAMPLE 2

5-ethyl, 5-(4',4'-dimethylpentyl) barbituric acid

The structural formula of this substance is as follows:

from which it is seen that it is the same as the preceding compound, Example 1, except for the addition of one further —CH₂— group in the alkylene chain connecting the quaternary carbon atom to the barbituric acid nucleus.

The synthesis of this substance is substantially the same as that of the next lower homologue (Example 1) as described, but involving the use of 4,4-dimethyl-1-bromopentane in place of the 3,3-dimethyl-1-bromobutane. First, the 4,4-dimethyl-1-bromopentane is condensed with ethyl ethylmalonate to obtain the ester having the formula:

and that is in turn condensed with urea to obtain the desired product. Because of the similarity of procedures, no detailed example of the synthesis of this material will be given.

The product, 5-ethyl, 5-(4',4'-dimethylpentyl) barbituric acid, is a crystalline solid having a melting point of about 184 to 185° C.

EXAMPLE 3

5-ethyl, 5-(4',4'-dimethylhexyl) barbituric acid

The structural formula of this substance is as follows:

from which it is seen that it is the same as the substance of Example 2, with the exception that one of the —CH₃ groups attached to the quaternary carbon atom has been replaced with a —CH₂CH₃ group.

The synthesis of this substance is substantially the same as that of the preceding examples, but involving the use of 4,4-dimethyl-1-bromohexane as the quaternary carbon-containing starting material. First, this substance is condensed with ethyl ethylmalonate to obtain the ester having the formula:

and that is in turn condensed with urea to obtain the desired product which has the form of long, colorless, fluffy needles melting at 154 to 155° C.

EXAMPLE 4

5-ethyl, 5-(7',7'-dimethyloctyl) barbituric acid

The structural formula of this substance is as follows:

from which it is seen that it is the same as the substances of Examples 1 and 2, except for the addition of four, and three, respectively, further —CH₂— groups in the alkylene chain connect-

acids falling within the scope of the invention. For example, if sodium ethylate be allowed to react, in molecular proportions, by well-known methods, with any of the foregoing acids, the monobasic sodium salt of the corresponding acid is obtained. The same is of course true of the other alkali metals. It is unnecessary herein to set forth specifically all of these alkali-metal-salts of all of the foregoing acids, but a few will suffice for the lot:

EXAMPLE 18

(From Example 1.) Monobasic sodium salt of 5-ethyl, 5-(3',3'-dimethylbutyl) barbituric acid.

EXAMPLE 19

(From Example 2.) Monobasic sodium salt of 5-ethyl, 5-(4',4'-dimethylpentyl) barbituric acid.

EXAMPLE 20

(From Example 13.) Monobasic sodium salt of 5-phenyl, 5-(4',4'-dimethylpentyl) barbituric acid, which is an amorphous white powder that decomposes on heating, yielding no well-defined melting point.

The malonic esters described in this application are claimed in the copending application of the present applicant Whitmore, and David M. Jones and Clarence I. Noll, Serial No. 63,212, filed February 10, 1936.

In view of the above, it will be seen that the several objects of the invention are achieved and other advantageous results obtained.

As many changes could be made in carrying out the above syntheses and in compounding the above substances without departing from the

scope of the invention, it is intended that all matter contained in the above description shall be interpreted as illustrative and not in a limiting sense.

We claim:

1. 5-ethyl, 5-(3',3'-dimethylbutyl) barbituric acid.

2. 5-ethyl, 5-(4',4'-dimethylpentyl) barbituric acid.

3. A substituted barbituric acid corresponding to the type formula:

15

wherein Y indicates a substituent selected from a class composed of hydrogen and the alkali metals, R indicates a substituent selected from a class composed of hydrocarbon radicals, aryl-oxy-alkyls, and alkyl-oxy-alkyls, R₁ is an aliphatic hydrocarbon radical, and R₂, R₃, and R₄ are each alkyls attached to the same carbon atom of R₁.

4. A 5-substituted barbituric acid having a single barbituric acid nucleus, in which one of the substituents in the 5-position is an aliphatic hydrocarbon radical having a quaternary carbon atom in its structure.

5. A 5-substituted barbituric acid having a single barbituric acid nucleus, in which one of the substituents in the 5-position is an alkyl having a quaternary carbon atom in its structure.

FRANK C. WHITMORE.

MELVIN A. THORPE.
